DESIGN FOR A CARD RECEPACLE

Robert C. Lafferty, New York, N. Y.

Application March 15, 1933. Serial No. 47,466

Term of patent 3½ years

To all whom it may concern:

Be it known that I, ROBERT C. LAFFERTY, a citizen of the United States residing at No. 141 West 96th Street, New York city, in the county of New York and State of New York, have invented a new, original, and ornamental Design for a Card Receptacle, of which the following is a specification, reference being had to the accompanying drawing, forming part thereof.

I claim:

The ornamental design for a card receptacle, as shown.

ROBERT C. LAFFERTY.
